RADIO TUNING DEVICE

Application filed January 7, 1927. Serial No. 159,585.

This invention relates to the tuning of radio frequency circuits and more particularly to a tuning element adapted to bring a radio frequency circuit into resonance.

5 One object of the invention is to provide in the tuning of radio circuits, for conductively coupling a tuning device to an aperiodic circuit to bring the circuit into resonance at any desired wave-length throughout any predetermined band of radio frequencies.

In one embodiment of the invention disclosed herein a variable capacitance or inductance or a combination of capacitance and inductance is conductively coupled both to 15 and aperiodic primary circuit and a grid circuit of an audion tube to simultaneously bring these combined circuits into resonance. The tuning element is particularly adapted to cooperate with a circuit in which a radio frequency choke having a high effective resistance at the customary radio frequency wave-lengths is used for impressing oscillations received in the primary circuit on the grid of an audion tube.

20 Other objects and advantages of the invention will be more fully set forth in the following description, in the claims, and in the drawings in which,

Fig. 1 is a diagrammatic showing of the 25 invention showing a capacitance and inductance conductively connected across a radio frequency choke in a combined antenna and grid circuit;

Fig. 2 is a diagrammatic showing of a 30 modification of the invention in which the capacitance and the inductance are connected in series across the radio frequency choke;

Fig. 3 shows a further modification of the 35 invention showing the tuning device connected across a radio frequency transforming coil in a grid circuit;

Fig. 4 is a side view showing the tuning element as an attachment connected to a radio-receiving set;

40 Fig. 5 is a side elevation of a form of tuning device in which the capacitance and the inductance are simultaneously varied in a proportionate manner; and

Fig. 6 shows the manner in which the 45 capacitance and the inductance are coupled

together on the same shaft so as to be simultaneously varied.

Referring more particularly to the drawings in which similar reference numerals represent corresponding parts in the various figures, one form of the invention is shown in Fig. 1 in which an audion tube designated generally 10 is provided with a grid 11 on which electrical oscillations are impressed so as to govern an output circuit 12 connected to the anode or plate 13 of the tube. The filament 14 of the tube is adapted to be heated from a battery or any suitable source of current not shown, so as to cause the emission of electrons in the customary manner well known in the art.

The grid 11 is connected by a wire 15 to the antenna 16 and a radio frequency choke 17 having a high effective resistance at the customary wave-lengths used in ordinary broadcasting reception is connected to the antenna and to the grid wires at 18. The opposite end 19 of the choke 17 is connected to the ground at 20 and connected to the wire 21 which leads to the filament 14 of the audion tube.

The radio frequency choke preferably consists of a large number of turns of small diameter fine wire so that its effective resistance at radio frequencies is in the neighborhood of 80 1,000,000 ohms, and the winding is preferably such as to produce an effective distributed capacity of a substantial value, represented in dotted lines at 25. The choke 17 in the combined antenna and grid circuits will thus 85 operate to connect the aerial to the ground so that a comparatively high voltage may be impressed on the grid 11 of the audion tube, the antenna and grid circuits however being adapted to operate aperiodically by reason of 90 the extremely high impedance or effective resistance of the choke 17.

In order to decrease the resistance of the path of the radio frequency waves between the antenna and the ground and also tune the 95 grid circuit of the audion tube 10, a tuning device designated generally 30 is connected across the points 18 and 19 of the circuit. This tuning device consists of a variable capacitance 31 connected in parallel with a 100

variable inductance 32 which are of such values that the combined aperiodic or primary circuit and tuning circuit may be brought into resonance at any desired wave-length for 5 which the radio set is adapted to operate. The tuning elements 31 and 32 are shown in Fig. 6 as connected on the same shaft 40 the capacitance 31 consisting of a series of movable plates 33 and fixed or stator plates 34, the 10 movable plates 33 being attached to the shaft 40 which is operated by a hand-operated controlling element 35 located, as shown in Fig. 5, on the front of the mounter case 36 so as to be easily accessible for tuning the apparatus. The same shaft 40 which bears the movable plates of the condenser 31 also bears the rotor inductance coil 41 which is connected in series with the fixed or stator coil 42 of 20 the inductance so that the inductance and the capacity of the parts 32 and 31 may be simultaneously increased or decreased in unison and in a proportionate manner to maintain the power factor of the circuits at a 25 maximum value. The inductance 32 and the capacitance 31 are adapted to be so varied that when tuned they will bring the combined antenna and grid circuit comprised of the antenna path to ground and the grid 30 input path simultaneously into resonance corresponding to the particular wave-length to which they are adjusted and thus permit both of these circuit paths to operate more efficiently and selectively, and to increase 35 the volume of the signals of the radio receiving or transmitting set with which the tuning device is used. The values of the capacitance 31 and inductance 32 are such that they may be adjusted simultaneously to 40 positions where the effective resistance at radio frequency of the combined tuning device is a very high value so that the antenna circuit and the grid circuit may operate aperiodically although connected to the tuning device. When the grid circuit operates 45 aperiodically the tuned condition of the grid circuit is no longer present as both the condenser and the inductance then offer high effective resistance in an untuned manner, to 50 radio frequency oscillations. Thus incoming radio signals may be impressed by means of the choke coil on the grid 11 of the audion tube due to the aperiodic manner in which the circuits function with the tuning device un- 55 tuned. The effective distributed capacity 25 of the radio frequency choke 17 is of a comparatively small value and is preferably insufficient to tune the grid or antenna circuits except for wave-lengths greater than those 60 adapted to be received. The choke 17 is adapted to provide a path from the antenna to the ground of somewhat less effective resistance for those radio frequencies of comparatively low wave-lengths to permit some 65 of the energy to escape at these low wave-

lengths and reduce tendencies of the radio-receiving set to oscillate, while still maintaining a more efficient reception at the higher wave-lengths.

The tuning device consisting of the variable tuning element or elements is provided as an attachment adapted to cooperate with existing radio sets, and as represented in Figs. 5 and 6 the tuning elements are mounted in a separate case or panel 36 which is provided at the rear thereof with the usual binding posts 37 to which the tuning elements are connected, and which are adapted to be quickly attached or connected to the radio set with which the attachment is to be used. 70 75 80

Obviously it is unnecessary to connect the capacitance and the inductance together exactly as shown in Fig. 1 as just described and although it is preferred to adjust the capacitance and the inductance of the tuning device in unison only one of these tuning elements may be operable to bring the antenna and the grid paths into resonance. 85

In Fig. 2 a modification of the invention is shown in which the grid 50 of the audion tube 51 is connected to a radio frequency choke 52 having a distributed capacity represented in dotted lines at 53. The antenna 54 instead of being connected directly to the end 55 of the choke 52 is connected to the tuning device 90 represented generally by the numeral 56, this antenna wire being connected first to a variable condenser 57 so that the different characteristics of antennæ of various lengths may be compensated to permit the use of a smaller 95 tuning condenser 61. The condenser or capacitance 61 is preferably variable and is connected in series in the modification shown in Fig. 2 with the variable inductance 63 which is connected at one end to the adjustable condenser 57 and to the grid circuit of the audion tube 51 at the point 55. The untuned antenna circuit through the condenser 57, the grid path and the radio frequency choke 52 to the ground at 64 may thus operate aperiodically when the values of the capacitance 61 and the inductance 63 are adjusted to provide a path having a high radio frequency effective resistance. When however the tuning elements 61 and 63 are adjusted to bring the combined antenna and grid circuits, to which they are conductively connected, into resonance, an increased efficiency of operation of the antenna and grid circuits will result and the volume of reception may be controlled, without interfering with the untuned aperiodic operation of these circuits when other tuning devices of the radio set such as the tuning elements 60 shown in Fig. 4 are operated to bring in any 100 105 110 115 120 125 desired signal.

In Fig. 3 another embodiment of the invention is shown in which the variable tuning device designated generally 70 consists of a variable capacitance 71 and an inductance 72 130

cooperating therewith, these tuning elements being connected across a part 73 of a radio frequency transformer coil 74 provided in the grid circuit 75 of the audion tube 76. The 5 antenna wire 77 is connected at the point 78 to the transformer coil 74 and to the tuning elements 71 and 72 so that the normally operating aperiodic antenna circuit through the part 73 of the coil 74, leading to the ground 10 79, may be brought into resonance or tuned to any desirable wave-length so as to increase the currents flowing through the coil part 73 which by the usual transformer action will cause a greater voltage being impressed 15 on the grid circuit 75 of the audion tube. A radio frequency choke 80 is shown conductively connected across the coil 74 and the grid circuit path for permitting the aperiodic operation of the grid circuit, such 20 operation of the choke 80 not interfering with the tuned operation of the circuits when the tuning elements 71 and 72 are in their tuning relation.

The various tubes 76 and 85 together with 25 other tubes which may be connected to the output of the tube 85 are shown coupled together so that the output circuit of the tube 76 is inductively connected to the grid or input circuit 86 of tube 85 and the output circuit 87 30 connected to the plate 88 of tube 85 is inductively coupled to the succeeding tube or tubes. The circuit 86 of the tube 85 is shown as including the radio frequency choke coil 89 connected across the grid circuit and the 35 choke coil combined with the secondary 90 of the radio frequency transformer 91 permit the normal aperiodic operation of the grid circuit. This grid circuit may be tuned or brought into resonance for any wave-length 40 received by the set by adjustment of the tuning device 92, corresponding to the tuning device 30 of Fig. 1 and consisting preferably of a tuning condenser or a combined tuning condenser and impedance variable together as previously described. After the 45 desired sending station has been tuned in by adjustment of the various dials which operate the tuning elements in the various tuned circuits of the set, the combined condenser and 50 impedance tuner located in the aerial circuit or in the other aperiodic circuits of the set may be adjusted to regulate the volume of the received signal and attain the maximum efficiency of operation. When the tuning devices 55 represented at 60 in Fig. 4 of the various tuned circuits of the receiving set designated generally at 90 in this figure, are simultaneously operated to adjust the various tuned circuits of the receiving sets proper to bring 60 in a desired transmitting station the tuning device connected to the aperiodic circuits are adjusted so that they have comparatively high effective resistances at radio frequencies so as not to disturb the aperiodic operation of these circuits. After the various 65

dials 60 of the receiving set have been properly adjusted to obtain maximum value of the signal then the untuned circuit or circuits may be tuned or brought into resonance for the desired signal by a proper manipulation 70 of the controlling dials 35 and the volume of reception may be regulated to any desired amount by further manipulation of these dials.

While the method herein described, and the form of apparatus for carrying this method into effect, constitute preferred embodiments of the invention, it is to be understood that the invention is not limited to this precise method and form of apparatus, and that changes may be made in either without departing from the scope of the invention which is defined in the appended claims.

What is claimed is:

1. In combination with a radio-receiver set 85 having an aperiodic antenna circuit containing a radio frequency choke with a grid circuit connected across said choke, a tuning attachment for said set comprising a tuning element independent of said choke and embodying an inductance and a condenser, means for quickly conductively attaching said tuning element to the antenna and the grid circuits, and means for adjusting the tuning element to bring the antenna circuit into resonance. 90
2. In combination with a radio-receiver set 95 having an aperiodic antenna circuit containing a radio frequency choke, with an untuned grid circuit connected across said choke, a tuning attachment for said set comprising a tuning element independent of said choke, means for quickly conductively attaching said tuning element to the antenna and the grid circuits, and means for adjusting the tuning element to bring the grid and the antenna circuits simultaneously into resonance, said tuning element comprising a variable capacitance and a variable inductance conductively connected together and variable in unison by said adjusting means. 100
3. In combination with an aperiodic antenna circuit for radio signaling having a radio frequency path therein of high effective resistance and a grid circuit conductively coupled thereto across the said path, of a variable tuning element independent of said path and comprising a condenser and an inductance connected in series across the said path to bring the combined grid circuit and antenna circuit into resonance at a desired 110 radio frequency. 115
4. In combination with an aperiodic antenna circuit for radio signaling having a radio frequency choke therein and a grid path conductively coupled thereto to the choke, of a variable tuning element independent of said choke and comprising a condenser and an inductance conductively connected across the choke to bring the grid and antenna circuit into resonance at a desired radio frequency. 125

quency, said tuning element having a negligible radio frequency effective resistance when tuned as compared to the choke, and adjustable to have a high effective resistance at radio frequency so that the antenna circuit may cooperate substantially aperiodically with the grid circuit.

In testimony whereof I hereto affix my signature.
